UNITED STATES PATENT OFFICE.

GILBERT S. ELLITHORPE, OF CHICAGO, ILLINOIS.

RUBBER HEEL.

1,254,489.

Specification of Letters Patent. Patented Jan. 22, 1918.

Application filed April 13, 1917. Serial No. 161,794.

To all whom it may concern:

Be it known that I, GILBERT S. ELLITHORPE, a citizen of the United States, residing at Chicago, in the county of Cook 5 and State of Illinois, have invented new and useful Improvements in Rubber Heels, of which the following is a specification.

My present invention pertains to cushion heels for boots and shoes; and it has for one 10 of its objects to provide an air-cushion heel which by virtue of its construction is possessed of a high degree of resiliency in proportion to its size.

Another object of the invention is the provision of a heel embodying such construction that the application and fastening of the heel to a shoe compresses air in the air chamber of the heel and thereby contributes to the elastic character of the heel.

20 Another object of the invention is the provision of improved means for effecting connection of the heel to a shoe.

Other objects and advantages of the invention will be fully understood from the 25 following description and claims when the same are read in connection with the drawings, accompanying and forming part of this specification, in which:

Figure 1 is a vertical section showing a 30 heel constructed in accordance with my invention as applied.

Fig. 2 is an inverted plan view of the same.

Fig. 3 is a view similar to Fig. 1 of a modification.

35 Fig. 4 is a plan view of a metallic or analogous plate embraced in said modification.

Referring by numeral to the said drawings and more particularly to Figs. 1 and 2, thereof:

40 Numeral 3, Fig. 1, is a portion of a shoe. 1 is my novel heel which is formed of vulcanized rubber or the equivalent thereof, and 2 is a layer of the same material that is interposed between the shoe portion and the heel.

45 In the heel 1 is provided a chamber 7 that is open at its upper side, and also formed in the heel and surrounding and following the contour of said chamber is a recess 4 which is open to the underside of the heel 50 and is closed to the upper side thereof.

In the inner portion of the recess 4 is arranged a metallic plate 5 which is shown as continuous though it may be made in sections arranged end to end in the discretion of 55 the manufacturer. I would also have it

understood that I do not restrict myself to making the plate 5 of metal inasmuch as the said plate may be made of other rigid material without departure from my invention as claimed.

60

The plate 5 is apertured as shown, and in the said apertures are disposed the headed nails or pegs 6 through the medium of which the heel 1 and the layer 2 are connected with the shoe portion 3.

65

I would further have it understood that my invention is not restricted to the employment of the layer 2, and that the improved heel may obviously be successfully used when the said layer 2 is entirely omitted, 70 and the opposition of the marginal portion of the heel 1 to the shoe portion 3 is depended on to confine air in the chamber 7.

An important feature of my invention is the recess 4 following the contour of the 75 chamber 7. By virtue of said recess it will be manifest that free compression and expansion of the air chamber 7 is afforded without compression and expansion of the rubber thickness of the heel 1. This obviously increases the elasticity of the heel, and at the same time renders the same light in weight and inexpensive to manufacture.

The plate 5 disposed in the innermost portion of the recess 4 serves for the engagement of the nails 6, and hence when the heel is nailed to the shoe portion there will be an even pressure distributed around the heel surface to maintain the same uniformly in contact with the heel, and incidentally, 90 when the chamber 7 is employed, the air chamber is preserved comparatively airtight.

The heel 1 shown in Fig. 3 is provided with an air-chamber 7 and a recess 4 similar to the corresponding features of the heel in Figs. 1 and 2, and said heel of Fig. 3 is also equipped with a plate 5 somewhat similar to the plate 5 described though differently arranged. It will also be noted 95 that the heel 1 of Fig. 3 is provided with apertures 9 that extend to the upper side of the heel 1 and are in communication with the recess 4. The said apertures 9 serve for the passage of the clips 10 on a thin plate 8 100 which is connected by nails 6 or other means to a shoe portion as a condition precedent to the application and fastening of the heel.

The clips 10 are preferably of the form shown and are springy in character, and 110

consequently when the heel is forcibly pressed over the clips 10 and against the shoe portion, the plate 5 will ride over the free ends of the clips 10 and will assume a position above the outwardly-directed ends of the clips whereupon the heel will be safely and strongly attached to the shoe portion. This construction is possessed of all the advantages ascribed to the construction of Fig. 1, and is further advantageous because it renders it feasible to effect the connection of the heel in a removable manner.

When deemed expedient I may employ a rigid plate 15 in the head portion of the heel 1 to stiffen said portion while permitting relative compression of the air chamber when any part of the tread is compressed.

Having described my invention, what I claim and desire to secure by Letters-Patent, is:

1. A heel of elastic material having a chamber in its side that is opposed to a shoe portion and also having a recess in its opposite side that surrounds and follows the contour of the said chamber, and a rigid plate arranged in the innermost portion of the said recess and also arranged and constructed for coöperation with heel attaching means to hold the heel firmly in contact

throughout its opposed surface with a shoe portion.

2. A heel of elastic material having a continuous recess in its underside, and a plate of rigid material arranged in the innermost portion of said recess and also arranged and constructed for coöperation with heel attaching means to hold the heel firmly in contact throughout its opposed surface with a shoe portion.

3. A heel of elastic material having a continuous recess in its underside, and a plate of rigid material provided with nail apertures, said plate being arranged in the innermost portion of said recess.

4. A heel of elastic material having a chamber in its side that is opposed to a shoe portion and also having a recess formed and arranged to allow of easy compression of the chambered portion, and further having embedded in its tread portion a rigid stiffening plate.

In testimony whereof I have hereunto set my hand in presence of two subscribing witnesses.

GILBERT S. ELLITHORPE.
